COVER RETAINING DEVICE

Milretta Rose Stroheim, Cincinnati, Ohio, assignor to The C. W. Zumbiel Company, Cincinnati, Ohio, a corporation of Ohio

Application December 12, 1956, Serial No. 627,883

2 Claims. (Cl. 206—65)

This invention relates to a device for holding a cover or lid in position on the mouth of a receptacle to protect the lid and receptacle from damage or breakage during shipment and handling.

One of the primary objectives has been to provide a device of this character which is simple, of inexpensive construction, and which may be applied or removed very quickly and conveniently.

The retaining device is intended particularly for containers or receptacles fabricated from ceramic materials, glass and the like, which may be chipped, cracked or broken when subjected to impacts. A conventional teapot formed of glazed ceramic material best discloses the principles of the invention and has been selected for purposes of illustration. The teapot disclosed herein comprises a thick-walled ceramic vessel having an open mouth delineated by an outwardly and upwardly flaring lip or brim, with a lid loosely fitted into the open mouth.

It is the usual practice, when packaging a number of teapots (or generally similar articles) in a container or carton, to pack a cushioning material between the several pots to prevent their glazed surfaces from contacting one another. Since the lid is fitted loosely in the mouth of each teapot, the lids may be enclosed in a soft wrapping material and placed in position in the mouth to prevent wrapping and damage. On the other hand, the lids may be packaged in the same carton but separate from the teapots.

When the teapots are to be placed on the shelf of the retail store for display and sale, it is necessary that the individual lids be unwrapped and placed in the position of normal use in the mouth of each teapot. It frequently happens that in handling the unpacked teapots in the retail store, the salesperson or purchaser may allow the loosely fitted lid to drop from the teapot causing breakage.

It is one of the specific objectives of this invention to provide a lid retaining device stamped from flat cardboard or other fibrous sheet material, which may be snapped in position over the top of the lid and into clinching engagement with the outwardly flaring lip to retain the lid securely in position during shipment and handling.

Another object has been to provide a retaining device which cushions the lid with respect to the mouth of the receptacle, while holding the lid downwardly in position, thereby to prevent rattling and possible chipping of the parts during shipment and handling. Briefly therefore, the retaining device may be applied to each receptacle or teapot when it is originally packed and may be left in position when the article is placed on display or sale, thereby protecting and keeping the parts from being separated until the teapots are in the hands of the ultimate user or purchaser. In addition to these advantages, the present retaining device is quickly and conveniently applied and removed and thereby eliminates the time and effort of wrapping and unwrapping the individual lids or covers.

The device of this invention takes advantage of the outwardly flaring or beaded brim of the receptacle to provide the clinching engagement of the retainer which over-

2

lies the loose lid or cover. In general, the device comprises a flat blank, including a central body and a pair of retaining bands which are delineated by severance lines and arranged to be sprung downwardly into clinching engagement with the lip or brim of the receptacle. The central body further includes a pair of cushioning flaps, also delineated by severance lines, which may be bent downwardly to reside between the opposite sides of the lid and mouth of the teapot to cushion and space the two surfaces from one another. The cushioning flaps preferably reside at right angles to the retaining bands, the arrangement being such that the bands exert a pull-down force upon the central body of the retainer, thereby holding the lid in position in the mouth of the receptacle, while the cushioning flaps prevent actual contact of the two parts. The retainers are preferably stamped in a simple manner from cardboard or similar sheet stock in a single blanking and cutting operation; they are furnished in flat condition to the user. The inside diameter of the retaining bands are approximately the same, or slightly smaller than the outside diameter of the lip over which they are to fit.

The retainer is applied to the lid or cover with the cushioning flaps bent downwardly, such that they reside at opposite sides of the lid. The lid and the retainer as a unit thereafter is placed in position in the mouth of the receptacle, the retaining band at one side is pulled downwardly to its brim-engaging position, then the retainer is shifted laterally to allow the opposite retaining band to be pulled down into engagement with the brim at the opposite sides. Since the cushioning flaps reside along opposite sides of the lid, they are disposed between the normal meeting surfaces of the lid and mouth of the receptacle to prevent rattling and possible damage during shipment and handling.

A particular advantage of the present construction arises from the fact that the retaining bands increase their gripping action with respect to the circular lip when the cover is pulled upwardly. The upward force upon the central body portion of the retainer creates a camming action between the surface of the flared lip and the bearing surfaces of the retaining bands which contact the lip. Accordingly, the lid is held firmly in place even if the teapot is held in an inverted position; in actual use, the retainer has sufficient strength to allow the receptacle to be lifted by its lid. On the other hand, the retainer may be removed very readily simply by pulling one of the retaining bands in a lateral direction to allow it to clear the edge of the lip or brim for release, then releasing the opposite band in the same manner.

For purposes of disclosure, the retainer is generally circular in shape conforming to the circular teapot brim for which it is intended. However, it will readily be apparent that the device may be applied to receptacles or similar articles of various shape, utilizing the principles of this invention, the retaining bands being shaped to fit the configuration of the brim to which it is clinched. The retainer which is selected to exemplify the invention preferably is provided with a panel which provides a printing surface for advertising or other information relating to the receptacle upon which the retainer is applied.

The various features and advantages of the invention are disclosed in greater detail in the following description, taken in conjunction with the drawings.

In the drawings:

Figure 1 is a perspective view showing the retaining device snapped in position upon a teapot to hold the lid in place.

Figure 2 is a plan view of the retainer blank as furnished to the user.

Figure 3 is a sectional view taken along line 3—3 of

Figure 1, illustrating the relationship of the cushioning flaps and upper portion of the teapot.

Figure 4 is a fragmentary sectional view taken along line 4-4 of Figure 1, illustrating the locking portion of the retaining bands in relation to the brim of the teapot.

Figure 5 is a fragmentary view similar to Figure 4, showing the retainer being applied to the teapot.

Described generally with reference to Figure 1, the teapot 10, which has been selected to illustrate the utility of the invention, is of conventional design, having a handle 11 and a pouring spout 12. As shown in Figures 2 and 3, the teapot is formed of glazed ceramic material having a relatively thick wall to retain heat. The top opening or mouth of the pot is delineated by a circular lip or brim 13, the upper portion of which flares upwardly and outwardly as at 14. The mouth includes an internal bead 15 which delineates an upwardly facing shoulder 16 to support the cover or lid which is indicated generally at 17.

The lid 17 also is formed of ceramic material and comprises a cylindrical skirt 18 having a top wall 20 which overhangs the cylindrical skirt in the form of a circular rim 21. Centrally of the top wall, a knob 22 of the usual profile projects upwardly from the lid, for convenient handling. The skirt portion 18 loosely interfits the opening delineated by the internal bead 15 and the rim 21 loosely interfits the inside diameter of the mouth above the internal bead 15. When in normal use, rim 21 of the lid rests directly upon the shoulder 16 of the opening. As shown in Figures 3 and 4, the retainer device, indicated generally at 23 confines the lid in position within the open mouth but spaces the lid surfaces from the surfaces of the mouth.

Referring to Figure 2, retainer 23 comprises a flat blank formed of sheet material, for example, heavy paper, cardboard, or other fibrous material. In the present example, the blank retainer 23, as furnished to the user, is generally circular and includes a panel 24 joined to the blank along the score line 25. The panel, which is generally square, provides an area upon which advertising material or the like may be printed. The blank is provided with a pair of arcuate cuts 26-26 spaced inwardly from the edge of the blank and concentric with its outer edge. The cuts or severance lines 26 delineate a pair of diametrically opposed retainer bands 27-27 and a central body 28. It will be noted that the severance lines 26 have their opposite ends spaced from one another; accordingly, the retainer bands 27 are joined to the central body between the ends of the severance lines at diametrically opposite sides as at 30. The central body of the blank includes an opening 31 to receive the knob 22 of the lid.

In addition to the retaining bands 27, the blank further includes a pair of cushioning tabs or flaps 32, the sides and end of each flap being delineated by the severance lines 33. Each flap 32 may have its outer end delineated by a score line 34, such that the flaps may be bent downwardly as shown in Figure 3. It will be noted that the flaps 32 are located at right angles to the opposed retainer bands 27. It will also be noted that the inner ends of the cushioning flaps 32 terminate short of the central opening 31 to provide the connecting sections 35 on opposite sides of hole 31.

In applying the retainer to the teapot, in the present example, the retainer is first slipped down over upon the knob 22 and over the lid. The lid may then be lifted from the open mouth to allow the cushioning flaps 32 to be sprung downwardly against opposite sides of the skirt portion 18 of the lid as shown in Figure 3. It will be noted that the cushioning flaps have sufficient length to extend downwardly a substantial distance below the rim 21 of the lid and along the skirt.

When the cushioning flaps are bent downwardly beneath the rim of the lid, they bend along their score lines 34; however, the score lines offer sufficient bending resistance

to cause the flaps to spring naturally toward one another and against opposite sides of the lid. Accordingly, the flaps offer no interference when the lid is placed in position in the open mouth of the teapot. In this position, as shown in Figure 3, the cushioning flaps 32 extend at an angle across the internal surface of brim 13 and across the internal bead 15 which delineates shoulder 16. Accordingly, the rim 21 of the lid rests upon that portion 36 of the flaps which yieldably span the internal bead and brim surface. Therefore, the lid is yieldably supported at diametrically opposite sides upon the yieldable portions 36 of the cushioning flaps.

It will be noted in Figure 4, that the arcuate severance lines 26 of the retainer bands delineate an inside diameter which is slightly smaller than the outside diameter 14 of the flaring brim 13. In applying the retainer, the retainer band 27 at one side is pulled downwardly with the fingers until it resides at the lower portion of the outwardly flaring brim 13. In Figure 5, the left hand retainer band, which includes the panel 24, is shown in full lines in its engaged position. After this band is engaged, the entire retainer is pulled to the right as indicated by the arrow, thus bringing the inner edge of the right hand band 27 in alignment with the upper edge of the brim. This band is then forced downwardly to the position shown in Figure 4 to its lip-engaging position. In this position, both bands spring upwardly into engagement against opposite sides of the flaring brim. It will be seen therefore, that the retainer takes advantage of the outwardly flared profile of the brim to provide positive engagement of the retainer bands. Moreover, the upward springing action of the bands tends to force the lid downwardly into engagement with the cushioning flaps.

The retainer creates a self-gripping action to prevent forcible removal of the lid, and in practice, will permit the entire teapot to be lifted without detaching the lid. When a pulling force is applied to the knob and lid as indicated by the arrow in Figure 4, the central body 28 of the retainer is bowed upwardly. This force creates a camming action of the bands against the flaring surface of the brim. As a result, the engaged portions of the bands are forced inwardly toward one another as indicated by the arrows in Figure 4, thereby increasing the clinching engagement of the bands in a proportion to the pulling force exerted upon the lid. The clinching force is substantially equal to the tearing resistance of the retainer, making it practically impossible for the lids to become accidentally displaced when the article is handled. On the other hand, if it is desired to remove the retainer it is a simple matter to force one of the bands upwardly with the fingers, when the other may be disengaged in the reverse order of that shown in Figure 5.

It will be observed that the device maintains its position by operation of the retaining bands and may be applied to receptacles in which the knob 22 is omitted from the lid. It will also be understood that the device is not limited in use to a receptacle having a circular brim since the configuration of the retaining bands can readily be altered to conform to non-circular brims. Moreover, usage of the device is not limited to the flaring brim disclosed herein; the retaining bands may be clinched with equal facility upon any upstanding brim which, in cross section, includes an overhanging bead or flange at some plane below the lid.

Having described my invention, I claim:

1. A retaining device for holding a detachable cover in the open mouth of a receptacle or the like, said mouth delineated by an upstanding circular brim which flares upwardly and outwardly, said retaining device comprising a flat blank formed of pliable sheet material, said blank having a pair of generally arcuate severance lines on opposite sides thereof, the opposite ends of said lines terminating in spaced relationship to one another, said severance lines delineating a generally circular central body and a pair of marginal, partially circular retaining

bands having endwise portions joined to said central body, said arcuate severance lines corresponding generally to the outside diameter of said circular brim, said central body including severance lines delineating a pair of cushioning flaps, said cushioning flaps residing at opposite sides of said central body and having outer ends integral with said central body and residing between the spaced opposite ends of the arcuate severance lines of the retaining bands, said central body residing over said detachable cover, said cushioning flaps being bent downwardly and disposed between the surfaces of the detachable cover and brim, said retaining bands being bent downwardly into clinching engagement over the external surface of the upwardly and outwardly flaring brim on opposite sides thereof, whereby said retainer device confines the cover within the said brim and against the cushioning flaps which are disposed between the surfaces of the cover and brim.

2. A retaining device for holding a detachable cover in the open mouth of a receptacle or the like, said mouth delineated by an upstanding brim having outwardly diverging portions, said retaining device comprising a flat blank formed of pliable sheet material, said blank having a pair of severance lines on opposite sides thereof,

said severance lines delineating a central body and a pair of marginal retaining bands having endwise portions joined to said central body, the retaining bands having internal edges corresponding generally to the external configuration of said upstanding brim, said central body including a pair of cushioning flaps having outer ends joined to said central body, said central body residing over the said detachable cover, said cushioning flaps bent downwardly and disposed between the surfaces of the detachable cover and brim, said retaining bands being bent downwardly into clinching engagement over the outwardly diverging portions of the brim on opposite sides, whereby said retainer device confines the cover within the said brim and against the cushioning flaps which are disposed between the surfaces of the cover and brim.
